CORE COVERING SPINDLE ADAPTER

Edwin G. Egge, Central Falls, R. I., assignor to
United States Rubber Company, New York,
N. Y., a corporation of New Jersey

Application June 18, 1948, Serial No. 33,792

5 Claims. (Cl. 57—18)

1

This invention relates to adapters for core covering spindles, and more particularly to a new type of adapter that supports a ring and traveller and can be applied to various types of core covering machines to enable them to be operated at higher speeds than heretofore.

Adapters have been used heretofore on various types of core covering machines, and are constructed to fit upon the rotating hollow spindle and inside of the yarn package so as to center the package upon the spindle. Such adapters have been used on the flier type of core covering machines, and on the ring and traveller type of core covering machines in which the ring is supported by the machine frame in a fixed position near the upper end of the yarn package.

The adapter of the present invention differs greatly from those employed heretofore, and one important feature of the present adapter resides in its thick disk-like construction whereby it has a wide outer periphery against which the covering yarn can rest and a deep annular recess in its upper face in which is mounted a traveller ring, so that the adapter supports and rotates this ring during the core covering operation. This rotation of the ring at the spindle speed greatly reduces the sliding movement between the ring and traveller.

Another feature of the present invention resides in the construction whereby the traveller ring is smaller in diameter than the disk-like adapter so that the yarn being unwound from the supply package can rest against the thick edge of the disk as it passes to the traveller rather than against the sharper edge of the ring.

Another feature of the present invention resides in the construction whereby the adapter is provided with an annular recess at its under face which is adapted to receive the protruding end portion of the yarn supporting tube, so that the adapter may lie close to the upper end of the yarn package.

Still another feature of the present invention resides in the construction whereby the ring and traveller lie slightly below the upper face of the adapter, so that lint and talc which lodge upon the upper face of the adapter and are thrown outwardly by centrifugal force will clear this ring and traveller to make this device self-cleaning.

The above and other features of the present invention will be further understood from the following description when read in connection with the accompanying drawings, wherein;

Fig. 1 is a side elevation of a motor driven type of core covering unit;

Fig. 2 is a vertical sectional view through most of the structure shown in Fig. 1;

2

Fig. 3 is a modification showing a core covering unit of the belt driven type; and

Fig. 4 is a vertical sectional view through most of the mechanism shown in Fig. 3.

The core covering spindle adapter of the present invention may be used on various types of core covering devices, and to illustrate this, is shown in Figs. 1 and 2 as applied to the motor driven type of covering unit and in Figs. 3 and 4 as applied to the whorl driven type of covering unit.

An important function of adapters for core covering spindles is to keep the yarn package accurately centered upon the rapidly rotating hollow spindle, and to this end adapters are constructed to fit snugly about the core covering spindle and snugly inside of the yarn package, or at least the upper end of such package. To accomplish this the construction of the portion of the adapter that engages the covering spindle and the inside of the package will vary in accordance with the size and shape of the package of core covering yarn used. This will be apparent upon examining Figs. 2 and 4 of the drawings.

Figs. 1 and 2 of the drawing which will now be described, represent the motor driven type of core covering unit having an electric motor, only the upper end of which is shown in the drawing, and is designated by the numeral 10. This motor has a central shaft which is hollow and projects upwardly a substantial distance from the motor casing to provide the integral, hollow spindle 11 adapted to support and rotate a yarn package 12 at high speed. The yarn of this package is wound upon the usual paper tube 13. The inner diameter of the tube 13 shown is considerably larger than the outside diameter of the hollow spindle 11. An adapter is therefore provided to support this package properly centered on the spindle 11.

The adapter as here shown comprises a thick disk-like head 14 and a barrel 15. This barrel has an inner bore adapted to fit the spindle 11 snugly and an outer bore that fits snugly within the paper tube 13, and the lower end of this barrel is notched to engage the usual driving key 16 provided near the base of the spindle 11. The upper end of the barrel 15 is formed with an enlargement 17 which fits within a correspondingly shaped hole formed in the head 14, and this head is glued or otherwise rigidly secured to the enlargement 17. The parts 14 and 17 are preferably so shaped that they will provide an annular recess 18 adapted to receive the upper end of the tube 13 where it projects a slight distance beyond the face of the yarn package. The disk-like head 14 of the adapter is preferably made of fiber since this material is tough and durable and its faces are not readily

dented, this head 14 however may be made of various plastic materials. The barrel 15 and enlargement 17 are preferably formed of wood.

The head 14 is made relatively thick as shown so that its outer periphery will form a wide guiding edge against which the covering yarn Y may rest, and also so that this disk-like head may be provided with a deep annular recess formed in its upper face and adapted to receive the traveller ring 19 upon which is mounted the usual traveller 20. This ring 19, it will be noted, is considerably smaller in diameter than the outer periphery of the head 14, and the ring is so positioned upon the head 14 that it lies an appreciable distance below the flat upper face formed by the top of the enlargement 17 and head 14. This arrangement is desired so that if lint or talc lodge upon the upper face of the head 14 they will be thrown outwardly by centrifugal force in a plane above the ring and traveller, to thereby make the device largely self cleaning.

The outside diameter of the adapter head 14 should be at least as large as the outside diameter of the full package 12, and by making the ring 19 smaller in diameter than the head 14, the covering yarn Y upon leaving the package 12 and passing upwardly to the traveller 20 may rest upon the wide outer periphery of the head 14 rather than against the narrow edge of the ring 19.

The core covering spindle 11 preferably extends upwardly a substantial distance above the upper end of the adapter so as to avoid bending the yarn sharply around the edge of the ring 19 as it passes from the traveller to the core covering position, and the upper end of the spindle 11 is preferably made tapered as shown. It is desirable to make the height of the spindle above the upper face of the adapter at least equal to, and preferably greater than, the radius of the ring 19.

The construction of the adapter of the present invention is such that the disk-like head 14 with its wide outer peripheral edge provides an excellent guide for the yarn Y as it is pulled off the package 12 and passes upwardly to the traveller 20, since by this construction it is held out of dragging engagement with the ring 19, and as the yarn passes upwardly from the traveller 20 to the tall spindle 11 it is further held out of contact with the ring 19 by the steep upward angle at which it travels. Upon reaching the upper end of the spindle 11 the yarn is wound about a core passing upwardly through this hollow spindle to thereby form the covered yarn C. As a result of the construction of the present invention the yarn Y is subjected to a minimum amount of tension during the core covering operation, and this enables the covering operation to be performed at very high speeds without causing excessive breakage of the covering yarn. Speeds in excess of 18,000 R. P. M. have been secured.

Having described the construction and operation of the motor driven type of core covering unit and adapter shown in Figs. 1 and 2, the whorl driven type of core covering unit and adapter shown in Figs. 3 and 4 will now be described, but it is desired to point out that while the construction shown in Figs. 3 and 4 for mounting the yarn package upon the hollow spindle is different from that shown in Figs. 1 and 2, the operation of the adapter so far as its action upon the covering yarn is concerned is substantially the same in all views.

In Figs. 3 and 4 the operating spindle is driven

by a whorl 21 which may be of usual construction and is rotatably supported by an antifriction bearing, not shown. The whorl has extending upwardly therefrom the whorl casting 22 in which is formed a central bore that receives a hollow spindle 23 that is press fitted into this portion of the whorl. To the upper face of the whorl 21 is rigidly secured a tube supporting disk 24 that has the upwardly extending prongs 25 and this disk has an opening that surrounds the casting 22. The covering yarn is supplied by a package 26 that is wound on the paper tube 27, and the prongs 25, which are four in number, snugly engage the inner bore of this tube.

The construction of Figs. 3 and 4 so far described serves to center the lower end portion of the package 26 about the spindle 23. The upper end of this package is centered by the adapter which will now be described. This adapter

consists primarily of a thick disc-like head 28

that may be made of fiber or other tough durable materials. This head 28 has rigidly secured to its lower face by means of screws 29, or other fastening means, a tube supporting disk 30 that has the downwardly extending prongs 30', and this disk has rigidly secured thereto the relatively long downward extending central tube 31 the inner bore of which is of a size to fit snugly about the hollow spindle 23. This permits the removal

of the adapter when a yarn package is to be changed.

The lower face of the head 28 is provided with the annular recess 32 which forms a clearing space for the protruding upper end of the tube 27. The upper face of the head 28 is

provided with a deep annular recess, in which is mounted the traveller ring 33, and on this ring is mounted the usual traveller 34. It is desirable, as above stated, to have the core covering spindle extend upwardly a substantial distance beyond

the upper end of the adapter head. This is accomplished in the construction shown in Figs. 3

and 4 by providing the tube extension 35 which fits snugly within a portion of the tube 31 and central hole formed through the head 28, to extend upwardly a substantial distance above the top of this head as shown. The thick outer edge of the head 28 acts the same as the similar thick outer edge of the head 14 to support the yarn as it approaches the traveller, and the yarn upon

leaving this traveller passes upwardly to the upper end of the spindle 35 where it is wound upon a core passing upwardly through such spindle to form a covered yarn.

Due to the construction of the present invention the covering yarn is subjected to very little tension as it passes from the yarn package to the core covering position, and as a result the core covering unit can be operated at very high speed without causing excessive yarn breakage.

Having thus described my invention, what I claim and desire to protect by Letters Patent is:

1. In combination with a core covering device having a hollow spindle adapted to support a package of covering yarn and rotate it about a core, an adapter comprising a thick disk having means for fitting said spindle and the upper end of the package to center the package upon the spindle, said disk having a deep annular recess in its upper face, a traveller ring of smaller diameter than the disk mounted in said recess to lie below said upper face, and a traveller for the covering yarn that travels upon said ring in a path that lies below the upper face of said disk and inwardly from its outer periphery.

2. In combination with a core covering de-

vice having a hollow spindle adapted to support a package of covering yarn and rotate it about a core, an adapter comprising a thick disk having means for fitting said spindle and the upper end of the package to center the package upon the spindle, said disk having a thick outer edge against which the yarn can rest and an annular recess in its upper face, a traveller ring of smaller diameter than the disk mounted in said recess, and a traveller for the covering yarn that travels upon said ring in a path that lies inwardly from the outer edge of the disk.

3. In combination with a core covering device having a hollow spindle adapted to support a package of covering yarn and rotate it about a core, an adapter comprising a thick disk having means for fitting said spindle and the upper end of the package to center the package upon the spindle, said disk having a thick outer edge against which the yarn can rest and an annular recess in its lower face adapted to receive a protruding end of the package, a traveller ring of smaller diameter than the disk mounted upon the disk, and a traveller for the covering yarn that travels upon said ring in a path that lies inwardly from the outer edge of the disk.

4. In combination with a core covering device having a hollow spindle adapted to support a

package of covering yarn and rotate it about a core, an adapter comprising a thick disk having means for fitting said spindle and the upper end of the package to center the package upon the spindle, said disk having a thick outer edge and a deep recess in its upper face, a traveller ring of smaller diameter than the disk mounted in said recess, and a traveller for the covering yarn that travels upon said ring in a path that lies inwardly from said thick outer edge so that the yarn may rest against this edge as it passes to the traveller.

5. In combination with a core covering device having a hollow spindle adapted to support a package of covering yarn and rotate it about a core, an adapter comprising a disk in the form of a head and having a barrel extending therefrom and adapted to fit said spindle and inside the package to center the package upon the spindle, said disk having a thick outer edge against which the yarn can rest and a traveller ring of smaller diameter than the disk secured thereto, and a traveller for the covering yarn that travels upon said ring in a path that lies inwardly 25 from the outer periphery of the disk.

EDWIN G. EGGE.
